UNITED STATES PATENT OFFICE.

WILLIAM E. NICKERSON, OF CAMBRIDGE, MASSACHUSETTS, ASSIGNOR TO GILLETTE SAFETY RAZOR COMPANY, OF BOSTON, MASSACHUSETTS, A CORPORATION OF MAINE.

HARDENING APPARATUS FOR THIN STEEL ARTICLES.

1,129,112.

Specification of Letters Patent. Patented Feb. 23, 1915.

Application filed February 16, 1906. Serial No. 301,487.

To all whom it may concern:

Be it known that I, WILLIAM E. NICKERSON, of the city of Cambridge, county of Middlesex, and State of Massachusetts, have 5 invented certain new and useful Improvements in Hardening Apparatus for Thin Steel Articles and by Heating and Chilling, &c., of which the following is a specification.

10 My invention relates to devices for automatically heating and hardening steel, and is specially adapted for those operations upon thin flexible razor-blades, such as the Gillette blades which are provided with 15 positioning holes or perforations.

While the invention will be described as applied to the heating and hardening of steel of that form, it is to be understood that with certain minor modifications the 20 machine may be used for like operations on other forms of steel or steel articles, and that some of its novel features are applicable for acting in other ways upon thin steel or other metal, such, for instance, as printing upon thin metallic articles.

It is ordinarily extremely difficult to transfer very thin steel quickly enough from the heating place to the chilling means to avoid loss of heat in transit, especially at the 30 edges, and any material loss of heat in transit vitiates the result of the hardening.

My invention is designed to overcome the difficulties mentioned and to produce an improved quality of hardening of the steel, or 35 steel articles, to which the machine may be applied.

The main objects of the invention are to retain a proper supply of razor-blades, or other forms of thin steel, and automatically 40 transfer them to means for heating and after being heated and while in a hot state to suitable means for chilling, such as cold-clamps, or, if desired, directly into a chilling liquid.

45 Other special objects of the improvement in this particular application of it are to produce quick and uniform heating of thin steel, and a quick chilling of it, in order to secure uniform temper; and further, to provide means for protecting the steel against the action of the air, and to avoid overheating or other injury as well as to compact the steel and avoid buckling, etc.

To these ends the invention consists in the 50 combinations of devices or means as herein-

after described and pointed out or indicated in and by the claims.

In the accompanying drawings Figure 1 is an elevation of the left side of the machine, or mechanism. Fig. 2 is a front elevation of the machine, and Fig. 3 a plan view thereof. Fig. 4 is a partial elevation on an enlarged scale of the right side of the machine with some parts broken, others removed, and others in section. Fig. 5 is an 60 enlarged plan view of the front half of the machine. Fig. 6 is a greatly enlarged view, partly in side elevation, and partly in vertical section looking in the same direction as in Fig. 4, and shows the cold-clamps or 65 chilling device and connections therewith not shown in Fig. 4. Fig. 7 is a side elevation of a blade carrying stack-plate with its latch mechanism locked, and Fig. 8 is a like view of the same, but showing the latch 70 mechanism unlocked. Fig. 9 is an enlarged plan of the latch mechanism for the blade carrying stack-plate shown in the two preceding figures, certain parts being removed as indicated by the line 9—9 in Fig. 7. Fig. 75 10 is a rear elevation of the blade carrying stack plate (parts being removed as indicated by the line 10—10 in Fig. 7) and shows means for releasing or unlocking the latch for the stack-plate. Fig. 11 is a much enlarged sectional elevation of the blade carrying-arm and preliminary heating burner, 80 which also appear in Figs. 3 and 5. Fig. 12 is a sectional elevation of a part of the blade carrying-arm taken on the line 12—12 of Fig. 11, and shows the suction terminal for 85 contacting with the steel or blade, and Fig. 13 shows this suction terminal of the carrying-arm by much enlarged inverted plan view thereof. Fig. 14 is an enlarged elevation mostly in section of the suction carrying-arm swung so as to bring its outer terminus over a heating plate, but not 90 dropped upon it, and Fig. 15 is a like view, 95 with parts broken, of the suction carrying-arm in the same position as in Fig. 14, except that its outer terminus is lowered in position for placing the steel blade on a heating plate. Figs. 16 to 20 inclusive are 100 diagrammatic views shewing the positions of the principal parts of the device at various periods during the cycle of operations, which positions may be more conveniently described toward the close of the descriptive 105 part of this specification.

The construction of the machine is such as to be readily separated into groups of members, and hence the different groups will be designated by a letter, and the different members, or parts, or related connections for each group, will be distinguished by the same letter with an appropriate cardinal number.

In the drawings A is the main supporting frame of the machine, A' a shelf-like top plate projecting frontward from the frame, and A² is a base plate upon which the frame is securely fastened (Figs. 1, 2 and 3). All of the working parts of the machine take their impulse, directly or indirectly from a main power shaft B, journaled in the arms B¹, B², which are bolted to the sides of the main frame A. The power shaft B is rotated by the gear B³, the latter being driven by the pinion B⁴ and pulley B⁵, which turn upon the stud B⁶, rigidly attached to the arm B'. A loose pulley B' also turns on the stud B⁶, and the driving belt may be guided onto this loose pulley whenever it is desired to stop the operation of the machine (Figs. 1, 2, 3 and 4).

The supply of steel in the form of razor-blades to be acted upon is arranged in stacks upon a stack-plate C, and the stacks of steel are alined and steadied by pairs of vertical pins C', C', projecting from the stack-plate (Figs. 1 to 5 and 7 to 10 inclusive). The stack-plate is rotatably mounted upon the vertical shaft C² and rests upon a friction washer C³, which is supported by the friction driving plate C⁴, the latter being rigidly mounted upon the vertical shaft C². The shaft C² is journaled in the vertical sleeve C⁵, upon the top of which the driving-plate C⁴ finds vertical support, the sleeve itself being securely bracketed to the front of the top-plate A¹ (Figs. 7 and 8).

The vertical shaft C² is given continuous rotation in a ratio of one to three, with the main power shaft, by the bevel gear C⁶ and pinion C⁷, the former being rigidly mounted on said vertical shaft and the latter on a horizontal shaft C⁸, journaled in a spur C⁹ of the sleeve C⁵ and in the bracket C¹⁰ fixed to the front of the top-plate A¹ (Figs. 1, 2, 3 and 4). The horizontal shaft C⁸ is continuously driven in equal ratio by the main power shaft B, by means of the chain C¹¹, the sprocket C¹² on the shaft C⁸, and an equal sprocket on a hub C¹³ on the shaft B (see dotted lines in Fig. 1). The stack-plate C is therefore adapted to rotate in a ratio of one to three with the main power shaft B, one rotation of the latter taking place to one complete cycle of movements of the entire device, and would rotate continuously in that ratio but for certain intermissions in its movement for the purpose of bringing the next successive stack of blades into position. This intermittent movement is regu-

lated by the action of the latch C¹⁴ which is adjustably pivoted on the pointed screws C¹⁵, C¹⁶, and has the weighted rear end C¹⁶. The latch engages with notches C¹⁷, C¹⁷, on the under side of the stack-plate C (Fig. 8), and when so engaged prevents the turning of the plate, the friction driving plate C⁴ slipping underneath it. The latch is, however, momentarily released from the notches C¹⁷-C¹⁷ three times to each rotation of the driving-plate C⁴ (though only once to a rotation of the main power shaft B) by the three downwardly projecting releasing bosses C¹⁸-C¹⁸ on the under side of the driving plate C⁴.

Figs. 7 and 10 show the latch in engagement, and Fig. 8 shows the latch thrown out of engagement by one of the releasing bosses C¹⁸. The disengagement of the latch by the passing boss is only momentary and the latch is ready to engage the next notch C¹⁷ by the time the latter has reached the latch. In this way the stack-plate is intermittently advanced one stack of blades at each cycle of movements of the device, the number of notches being equal to that of the blade stacks. The blades are lifted from the stacks on the plate C and transferred to a heating plate by the movable suction carrying arm D, which is rigidly supported upon the upper end of the vertically reciprocating and partially rotating rod D¹, the latter being slidably and rotatably mounted in the top plate A¹ at D² and at D³ in the fixed arm D⁴ which is securely bolted to the main frame A (Figs. 1 to 5 inclusive).

The rod D¹ is given its vertically reciprocating motion, as well as that of partial rotation, by a novel combination of cams, levers, pull rods and arms which will now be described in detail. On the rod D¹ is rigidly mounted a hub D⁵ having opposite horizontally projecting arms D⁶ and D⁷. The arms are provided with a hub D⁸ and D⁹ respectively, the latter having horizontal radially disposed bores adapted to act as bearings for the forked trunnion pieces D¹⁰ and D¹¹. The forked ends of these trunnion pieces are supplied with pointed pivot screws D¹², which pivotally support the sleeves D¹³ and D¹⁴ through which the inclined pull rods D¹⁵ and D¹⁶ pass loosely, having the threaded clamp nuts D¹⁷ and D¹⁸, respectively, which prevent them from being drawn out of the sleeves farther than desired. The pull rods D¹⁵ and D¹⁶ are respectively connected by the universal joints D¹⁹ and D²⁰ with the levers D²¹ and D²² which are pivoted to the main frame at D²³ (Figs. 1 and 2) and D²⁴ (Figs. 2 and 4) and are provided with the rollers D²⁵ and D²⁶ which bear on the cams D²⁷ and D²⁸ (Fig. 2), the latter being keyed upon the main power shaft B. By this arrangement the rod D¹ is vertically supported by the levers

D²¹ and D²² through the inclined pull rods D¹⁵ and D¹⁶. When the two levers D²¹ and D²² are level with each other, then the pull rods will hold the parts by which they are connected with rod D¹ square to the front, so to speak, and these parts and the pull rods and levers will be in the position shown in the enlarged side elevation represented in Fig. 4. If, on the contrary, the lever D²¹ is lower than the lever D²² the rod D¹ will be lowered somewhat and partly rotated and the parts will be in the positions shown in Figs. 1 and 2. When the lever D²² is lowered from the position shown in Fig. 4, the lever D²¹ remaining as shown, then the rod D¹ will again be lowered but rotated in a reverse direction from that shown in Fig. 1. Hence, by raising or lowering the levers D²¹ and D²² simultaneously, reversely, or separately, any desired elevation or partial rotation of the rod D¹ may be produced within the limits of movement of the mechanism, for the purpose of causing the arm D to move freely from the stack-plate to a preliminary heating plate and to the final heating plate and back again. Of further assistance in regulating the movements of the rod D¹, and, thereby, of the suction carrying arm D, are certain guide posts, of which D²⁹ and D³⁰ serve to exactly locate the arm D when it drops upon the stack plate C and D³¹ and D³² which perform a like function when the arm D places a blade upon a heating plate (Figs. 1, 2, 3, 4, 5, 14 and 15). The guide posts D²⁹ and D³⁰ and D³¹ and D³² project vertically from and are integral with the pedestals D³³ and D³⁴, respectively, the former serving to support the stack plate latch C¹⁴, as shown in Figs. 7 and 8, and the latter for a mounting for some parts to be described. The pedestals are bolted to the upper surface of the top plate A¹ as shown in Fig. 5. When the arm D swings over the stack plate C it first strikes against the long guide post D²⁹ and then drops between it and the short post D³⁰ being thus exactly located. In swinging in the opposite direction to place a blade on a heating plate it is similarly guided and located by the posts D³¹ and D³². It is, of course, understood that the cams D²⁷ and D²⁸ are so fashioned as to give the required movements to the respective levers and pull rods and, hence, to the rod D¹ and arm D. The arm D does not move exactly horizontally when it swings from the stack plate C to a heating plate and back, but describes a curve, being highest when midway of the swinging movement, at which point it pauses for some time after swinging away from the stack plate, for the preliminary heating of a blade. In practice the cams are shaped to throw the arm D a little farther than is required to simply reach the long guiding posts, the difference being taken up by the inclined pull rod D¹⁵ or D¹⁶ slipping downward through the sleeve D¹³ or D¹⁴, respectively. This is done to make sure that the arm D actually reaches the long guide posts in each case. The pull rods D¹⁵ and D¹⁶ have independent movements and are inclined toward each other at their upper ends and also have an inclination toward the front. The upper ends move in vertical plane and describe an inclined arc, while the lower ends have a combined vertical and lateral or swinging movement about the axis of the rod D¹ thereby giving to that rod a combined vertical and rotary movement. The construction of the suction carrying arm D is shown in the sectional views of Figs. 11 to 15. The arm D has a downwardly projecting outer part, the lower end or terminus D³⁵ which is broadened laterally and serves as a surface against which to suck the blade in order to lift and transport it. The suction is produced by any suitable pump or blower not a part of my device, but connected with the arm D by means of the flexible tube D³⁶ and pipe D³⁷, the latter being screwed at its upper end into the arm D where it connects with passageway D³⁸ from which the branches D³⁹, D³⁹ run down to the face or terminus D³⁵, which is provided with recesses, as D⁴⁰ (Fig. 13) whereby the extent of surface of the blade to be lifted which is exposed to suction is increased. It is also provided along its edges with the projections D⁴² to prevent lateral displacement of the blade while in transit to a heating plate, and also with two vertical perforations D⁴¹, D⁴¹, through which the stack plate pins C¹, C¹, pass when the arm D drops onto a stack of blades (Figs. 11, 12 and 13). In order to release the blade the suction is shut off from the face D³⁵ when the blade is being placed upon a heating plate by the arm D. This is accomplished by the valve D⁴⁴ which consists of a cylindrical piece having the encircling groove D⁴⁵, the heavy top piece D⁴⁶, the stem D⁴⁷ and the flattened side D⁴⁸. This valve is slidably mounted in a cylindrical chamber which extends vertically from the upper side, intersecting the passageway D³⁸, to the under side of the arm D, in such a manner that when the valve is normally resting on its top piece D⁴⁶, as shown in Figs. 11 and 14, the groove D⁴⁵ is registered with the passageway D³⁸ and the suction can act freely. The valve is in this position at all times, excepting at the moment when the arm D is placing a blade on a heating plate. It is then forced up on the descent of the arm D, by the adjustable screw D⁴⁹ mounted in the pedestal D³⁴ and valve stem D⁴⁷ (Fig. 15), and the groove D⁴⁵ thereby carried above the passageway D³⁸, the main body of the valve closing the latter and shutting off the suction. At the same time the flattened part D⁴⁸ of the valve

reaches the passageway D^{38} on the side of the valve toward the blade, so that air may rush in from the outside and destroy all suction allowing the blade to drop off the face D^{35} readily. When thin, flat articles, for example the blades described, are piled in stacks, they tend to adhere together more or less, so that there is danger of lifting more than one at a time. This difficulty may be and is 10 overcome by slightly curving the face D^{35} in one plane, or forming it of slightly inclined intersecting planes as shown in Fig. 12. When the face D^{35} is so formed, the top blade of the stack is accordingly flexed 15 against it and so released from the blade under it, since a curved surface does not tend to adhere to a flat surface. The arm D is provided with a laterally projecting guard lip D^{30} located near the suction face D^{35} 20 which serves to protect the blade from the direct action of the flame when first placed upon a heating plate (Fig. 14). When the arm D drops to a heating plate its descent is limited by the stop pin D^{51} adjustably 25 mounted in the pedestal D^{34} (Figs. 14 and 15), but when, on the other hand, it drops upon a blade stack it simply comes to rest upon the top of the stack whether the stack be high or low, any excess of movement of 30 the levers D^{21} and D^{22} (Fig. 1) being taken up by the downward sliding of the pull rods D^{15} and D^{16} through the sleeves D^{13} and D^{14} respectively.

My device as herein illustrated and 35 described is provided with two separable heating plates, the under or receiving plate E and the upper or tossing plate F (Figs. 2 to 5). These plates E and F are made preferably of any metal or alloy capable of resisting 40 the action of a degree of heat sufficient for the process of steel hardening, such as platinum, nickel or some steel alloys. In the present case they are made, in plan, of a shape similar to the blades to be hardened, 45 but a little larger so as to overlap the blades (Fig. 5) and either of them may be recessed (as indicated in Fig. 14) to a depth about equal to the thickness of and over an area slightly larger than the blade, so that the 50 latter may be wholly inclosed and protected when between the heating plates. The plates are provided with the arms E^1 , E^1 , and F^1 , F^1 , respectively, which are attached one on each side of each plate and then bend 55 so as to run longitudinally with the plate. These arms are preferably integral with their respective plates and serve to connect the latter with their moving mechanisms. They join the plates at the sides, as shown, 60 in order that both ends of a plate shall be equally heated. The plate F can best be seen in enlarged plan Fig. 5, the similar plate E underneath it being hidden in this view, the side elevations of both plates being 65 shown separated in Fig. 4.

The heating plates E and F are connected by their arms E^1 and F^1 to the pivoted levers E^2 and F^2 , respectively, both of the latter being adapted to swing on and over the same pivot shaft G and thus reverse 70 their top and bottom positions. The lever E^2 has a single bearing on the central part of the pivot shaft G, while the lever F^2 is bifurcated and has two bearings on the shaft G, one on each side of the lever E^2 (Figs. 3 75 and 5). The shaft G is preferably tubular for the passage of a cooling fluid, and is rigidly supported at G^1 and G^2 by the posts G^3 and G^4 , which have a base G^5 in common, the latter being bolted to the top plate A^1 80 (Figs. 1 to 5).

The lever E^2 , by which the heating plate E is supported is given motion around the pivot shaft G by two devices. In the direction of the heating position, shown in Figs. 85 1, 2, 3 and 5, motion is imparted by the cam E^3 on the power shaft B (Fig. 2) acting upon the lever E^4 , pivoted at E^5 , by means of the roller E^6 , the outer end of the said lever E^4 being connected with the plate 90 carrying lever E^2 by the chain E^7 (Fig. 5), the latter being attached to the pulley E^8 which is integral with the said lever E^2 motion is given to the lever E^2 in the reverse direction by the weight E^9 and chain E^{10} , one 95 end of the latter being attached to the under side of the top plate A^1 and the other end to the pulley E^{11} , also integral with the lever E^2 , but wound upon it reversely to the chain E^7 , on the pulley E^8 , the said weight E^9 depending by means of the pulley E^{12} from the loop of the chain E^{10} as shown (Figs. 1 to 5). The cam E^3 is shaped to move the arm E^2 as required and hereinafter noted, and the weight E^9 is always tending to move 105 it in the reverse direction.

The heating plate F, through its lever F^2 , is operated in a way similar to that used with the plate E, excepting that the direction of the movements given by the cam and weight are reversed from what they are in the case of the plate E, that is to say, the weight tends toward the heating position, and the cam movement toward the inverted position. The operating parts connected 110 with the lever F^2 of the heating plate F are as follows: Away from the heating position; the cam F^3 (Fig. 2), lever F^4 pivoted at F^5 , roller F^6 , chain F^7 , pulley F^8 integral with lever F^2 ; and toward the heating position, 115 weight F^9 , chain F^{10} (Fig. 2), pulley F^{11} integral with the lever F^2 , and pulley F^{12} (Figs. 1 to 5). The weight chains E^{10} and F^{10} pass over the idler pulleys E^{13} and F^{13} , respectively, these pulleys being mounted in 120 a bracket attached to the under side of the top plate A^1 , in order to bring said chains into proper alignment with their respective weights E^9 and F^9 (Figs. 1, 2 and 4).

The heating plate E is provided with two 125

short pins E^{14} , E^{14} with rounded or pointed ends which, when the plate is in the heating position, project upward, and are shown in Figs. 4 and 14, and by dotted lines in Figs. 5 and 15. These serve to locate the blade, which has corresponding holes, accurately on the plate E when placed there by the suction carrying arm D. The heating plate F has one pin F^{14} similar to the pins E^{14} , E^{14} , which is located centrally in the plate and projects downward when the plate F is in the heating position, and upward when it is in the reverse or tossing position, and, by passing through a central hole in the blade, serves to keep the blade in place on the plate until it is tossed off. The heating plates each have recesses to receive the pins of the other plate when they shut together on a blade. As it is difficult to quickly separate the thin flat blades from an unbroken flat surface, the heating plates E and F are preferably perforated with numerous small air holes as shown in the plate F (Fig. 5). These perforations admit air for releasing the blade quickly from the heating plates and cause no material detriment by the admission of hot gases or flame during heating. Corrugating the surfaces of the plates throughout is effective, but the perforations are preferred as there is less interruption of the heating surfaces of the plates. By having a pair of separable heating-plates the steel is protected against undue curling by the action of the fire and may be kept very nearly to its normal flatness. It is not, however, indispensable for all practical purposes that the steel should be kept entirely from contact with the fire and any form of heating plate or plates which will serve the purpose may be employed.

The devices for heating consist of the gas burners H and H^1 and the preliminary burner H^2 (Figs. 1 to 5 and 11 and 14). These burners consist, substantially, of gas chambers into which a suitable mixture of gas and air is brought by pipes, the chambers having numerous small apertures or exits opening from them in the direction in which it is desired to have the flame extend, Fig. 14. The burners H, H^1 and H^2 are supported by their supply pipes H^3 , H^4 and H^5 , respectively, in such a manner as to be slightly adjustable as to position, the said pipes being held by collars H^6 , H^7 and H^8 which are fastened to the top plate A¹ in such a way as to be movable to a limited extent laterally, and to allow the pipes to be moved up or down, or turned as desired.

The burner H is located directly under the receiving plate E, and having its apertures on the top side the flame impinges on the under side of said heating plate (Figs. 5 and 14). The burner H^1 is so placed, and its apertures so arranged, that the flame is directed in an inclined position downward

upon the heating plates (Fig. 14), the burner H^1 itself being kept out of the path of the heating plates E and F as they swing upward and over on their pivoted levers E² and F².

The preliminary heating burner H^2 is provided with a heating plate H⁹ supported above the burner by the rods H¹⁰, H¹⁰ (Figs. 4, 5 and 11). This plate H⁹ is used to warm up the blade while being carried by the suction arm D from the stack plate to the receiving plate E. The cams operating the carrying arm D are so fashioned that the arm pauses a short time over the preliminary heating plate H⁹ in order to warm up the blade, and so reduce the time and heat which would otherwise be necessary while it is between the heating plates E and F. The plate H⁹ is to prevent the flame of the burner H^2 from impinging directly upon and injuring the thin blade, the latter being warmed by radiation from the hot plate. A fire back H¹¹ made of tiles, firebrick, or, other suitable material is mounted on the top of the machine in such relation to the heating-plates E and F when in heating position, and to the burners H and H^1 as to reflect and intensify the heat and prevent the flame from extending to or injuring other parts.

The preferred device for chilling, compacting and flattening the blades after they have been heated by the heating plates E and F, consists of two thick plates of steel or other suitable material, I and J (Figs. 1, 4 and 6), the former being rigidly secured to the main frame A, as shown in Fig. 6, and the latter firmly bolted to the massive pivoted arm J¹ which swings upon the strong pivot pin J², supported by the arms J³, J³ projecting from the main frame A. These plates I and J, will be termed cold-clamps. The pivoted arm J¹, which carries the cold clamp plate J, is so balanced upon the pivot pin J² that its clamp tends to descend, but is supported by the elbow lever arm J⁴ which engages with it by means of the roller J⁵ located at its outer end. The lever J⁴ is pivoted or fulcrumed on the pin J⁶ which is supported by the bracket J⁷, the latter being bolted to the main frame as shown in Figs. 4 and 6. The inner end of the lever J⁴ is connected with a heavy adjustable weight J⁸ which by proper connections is made to slide vertically in the frame A. This weight connects with the arm by a strap J⁹, one end of which is fastened to the main frame at J¹⁰, and which, after passing under the pulley J¹¹, mounted on the weight, is attached to the arm J⁴ by means of the shackle J¹² and pin J¹³. The strap J⁹ is deflected into alignment by the idler pulley J¹⁴ mounted on the main frame A, as shown (Figs. 1, 2, 4 and 6). The weight J⁸ gives the lever arm J⁴ a strong tendency to throw the cold clamp 130

plate J up against the similar plate I, but this can only happen at intervals, on account of the cam J¹⁶ mounted on the main power shaft B, which engages the inner end 5 of the arm J⁴ by means of a cam rib J¹⁰ projecting laterally from the side of the cam and extending in a semi-circle about half way round it. The end J¹⁷ of the cam rib lifts the inner end of the arm J⁴ when it 10 has been depressed, by the weight J⁸ thereby lowering the roller J⁶ at the other end of the arm, allowing the cold clamps to open as shown in Fig. 6. As the cam turns, the lever arm J⁴ is supported by the cam rib J¹⁰ against the action of the weight J⁸ until 15 the arm drops off the end J¹⁸ of the rib, at which time the said weight, acting freely through the lever arm J⁴ and its roller J⁶ closes the cold clamps with great force, compacting and flattening the hot steel in the 20 instant of chilling. The chilling action takes place when the cold-clamps are closed upon the hot steel, which after chilling is released when the end J¹⁷ of the cam rib J¹⁰ 25 lifts the inner end of the lever arm J⁴ as before stated.

The cold clamp plates I and J are kept cool by running a stream of water through passageways in them or by other suitable 30 means. The water as shown comes in the flexible tube I¹ which is connected by a suitable nipple with a passageway in the plate I, after traversing which it is conducted by the flexible tube I² to a passageway in the plate 35 J, on emerging from which the tube G⁶ delivers it to the tubular pivot shaft G, and after it has run through the latter it is carried away by the tube G⁷.

The scale, which "strikes" or becomes detached from the blades more or less as they 40 are being chilled by the cold clamps, is blown off the clamps as well as adhering blades, by an air blast delivered across the plate J by the blast pipe K, which is inserted in the clamp arm J¹, as shown in 45 Fig. 6, and is connected by the flexible tube K¹ with the valve K², said valve being raised and opened at the proper time by the cam K³ on the shaft B acting through the 50 roller K⁴, arm K⁵, rock shaft K⁶ mounted on the arm B², and lever K⁷. Air under pressure is supplied to the valve K² through the tube K⁸ (Fig. 6). When blades or steel drop from the opened cold clamp J, as 55 shown in Fig. 6, they are caught in a receiver L from which they are conducted by a spout L¹ into a receptacle L² supported by a bracket L³ bolted to the main frame A (Figs. 1, 2 and 3).

60 Mounted upon the top of the main frame A, by means of the bracket J¹⁹ is the pivoted detent arm J²⁰, having the shoulder J²¹, adapted to engage with the rear end of the cold clamp arm J¹ and prevent the clamp 65 from closing when the cam J¹⁶ releases the

lever arm J⁴. This is desirable sometimes, as when adjusting parts of the general device. In Fig. 1 the detent is shown operative by the dotted lines, and inoperative by the full lines. For similar reasons the rod 70 D¹, on which the suction carrying arm D is mounted, is provided with a stirrup-like yoke D embracing the end of the fixed arm 75 D⁴ to which it is pivoted (Figs. 1 and 2), and normally hangs against the rod D¹. When, however, it is desired to throw the arm D out of commission without stopping the general device, it is only necessary to lift the rod D¹ by the hand a little higher than its normal travel, and the yoke D⁶² 80 will swing under the end of the rod and by supporting it, prevent the action of its moving cams upon it, the pull rods D¹⁵ and D¹⁶ simply sliding up and down through their respective sleeves D¹⁸ and D¹⁴. 85

The diagrams, Figs. 16 to 20, show the principal elements of my device in various progressive positions. Fig. 16 shows the arm D on the stack plate, the heating plates in the heating position and the cold clamps 90 open. Fig. 17 shows the arm D over the preliminary heating burner, the heating plates swung over and ready to separate. Fig. 18 shows the heating plate F tossing a blade between the cold clamps. Fig. 19 95 shows the cold clamps shut on a blade and the arm D placing a blade on the returned heating plate E. Fig. 20 shows a blade dropping from the just opened cold clamps, with the next blade heating between the 100 plates E and F, and the arm D again on the stack plate.

The general mode of operation of my device is as follows: Starting with the suction carrying arm D, resting upon a stack of 105 blades on the stack plate C, as shown in Figs. 1, 2, 3, and 5, and in the diagram Fig. 16, a blade will be heating between the plates E and F, which are shut together and in the heating position, and the cold clamps I and J will be separated and ready to receive a hot blade to chill and compact; the suction carrying arm D rises by the action of the lever D²² and its respective cam and pull rod, until it has cleared the stack pins 110 C¹, C². Then the lever D²¹ swings it in an upward curve to a position about half way to the heating plate E, in which position it pauses, as before stated being directly over the preliminary heating burner H² and hot plate H⁹, the blade meantime warming up 115 (see Fig. 4). While the arm D is pausing over the hot plate H⁹, the heating plates E and F operate for the delivery of the heated blade. The plate F, impelled by its cam F³ 120 and connecting parts swings up and over and is closely followed by the heating plate E impelled by its weight E⁹, the hot blade being carried between them. The plate E follows the plate F until they have swung 125 130

about a half circle when the plate F pauses, through the action of its cam E³ and is swung back by said cam to the heating position again; the blade, however, as the arms are inverted when they separate, goes on with the heating plate F to its extreme position shown by full lines in Fig. 4. Fig. 4 also shows the heating plate E in the position in which it pauses to separate from the plate F, just before returning to the heating position. When the plate F reaches its extreme position shown by full lines in Fig. 4 the roller F⁶ on the lever F⁴ drops suddenly into a notch (not shown) in the cam F³, which allows the weight F⁹ to give the heating plate F, upon which the hot blade is lying, a quick jerk upward to the position shown by dotted lines in Fig. 4, where it is abruptly checked by the cam action. This sudden short swing and sudden checking of the plate F tosses the hot blade upon it in an upward and outward direction between the opened cold clamp plates I and J. The position of the blade or steel at this moment is shown by dotted lines in Fig. 4. As the plate F tosses the blade as aforesaid, the end of the arm J⁴ drops off the end J¹⁷ of the rib J¹⁶ of the cam J¹⁵, and allows the weight J⁸ to quickly and forcibly close the cold clamp plates, thus catching the blade between them, where it is compressed and chilled. By referring to the diagram, Fig. 19, it will be seen that when the arm J⁴ closes the cold clamps, it comes into a position under the arm J¹, in which it stands from its pivot at about a right angle to the engaging surface of the arm J¹, with which it engages by means of its roller J⁶. This position of the arm J⁴ causes great pressure and a locking effect whereby rebounding of the cold clamp plate J is practically impossible, while the plates are forced together on a blade. While the heating plate F is tossing the blade into the cold clamps, the plate E returns by the action of its cam to the heating position, and the carrying arm D moves in a descending curve to a position over it, said movement being caused by a descent of the lever D²², and the said arm after engaging with the guide post D³¹ drops down upon the heating plate E by the lowering of the lever D²¹ and deposits its partly heated blade thereon, the latter being released from the arm by the action of the valve D⁴⁴, as before described. After these movements the carrying arm D rises again by the ascent of the lever D²¹, and then swings to the intermediate position by the rising of the lever D²²; next swings over and downward to the guide post D²⁹ by the lowering of the lever D²¹, and finally drops onto a blade stack by the descent of the lever D²². While the carrying arm D was away from the stack plate, however, the latter has rotated enough in

the manner hereinbefore described to bring the next stack of blades into position for the arm to rest upon it. As soon as the carrying arm D has moved away from the heating plate E, the plate F, after tossing the blade, is swung back to the heating position by its weight F⁹, and closes down over the blade which the arm D had just placed upon the plate E. The end J¹⁷ of the rib J¹⁶ of the cam J¹⁵ now lifts the inner end of the elbow-lever arm J⁴ and allows the cold clamp plate J to drop and the chilled blade to slide off into the receiver L whence it is conducted to the receptacle L² by the spout L¹. As the cold clamp plates separate the cam K³ opens the valve K² and a blast of air is blown across the clamp-plate I from the blast pipe K, to remove dirt, scale or an adhering blade, and the movement cycle is complete.

While I have described my invention as operating upon razor-blades, I desire to have it understood that I claim it or certain features thereof, when applied for use on any other article that it is or can be adapted to handle with advantage, what I claim being:

1. In a machine for acting upon thin metal, the combination of a rotary stack plate for holding and supplying different stacks of metal to be acted upon, means for rotating said stack plate, means for holding the metal while being acted upon, means for acting and producing a desired effect upon the metal and means for transferring the metal from the stack to the means for holding the same during action.

2. In a machine for acting upon thin metal, the combination of a rotary stack plate for holding and supplying different stacks of metal to be acted upon, means for rotating said stack plate, means for holding the metal while being acted upon, means for acting and producing a desired effect upon the metal, a carrying arm for conveying the metal from said stack plate to the means for holding the same during action and means for operating said carrying arm to and from the metal on the stack plate.

3. In a machine for heating steel the combination of a stack-plate for the supply of steel to be heated, a heating plate adapted to receive the steel and hold the same while being heated, a lifting and carrying-arm adapted to take the steel from said stack-plate and transfer it to said heating-plate, and means for operating said carrying-arm.

4. In a machine for heating steel, the combination of a stack-plate for the supply of steel to be heated, means for supporting the steel while heating, means for transferring the steel from the stack-plate to said supporting means, and means for warming the steel after leaving the stack-plate and prior to its placement on said supporting means.

5. In a machine for heating steel, the combination of means for holding a supply of steel, means for handling and placing the same, means for warming the steel while in transit, and means for holding and heating the steel after placement. 70
6. In a machine for heating steel, the combination of a rotary stack-plate for holding stacks of steel, means for imparting intermittent rotary motion to said stack-plate, means for taking the steel therefrom and placing the same, and means for heating the steel after placement. 75
- 10 7. In a machine for heating steel, the combination of a rotary stack-plate for holding stacks of steel, means for retaining each stack on said stack-plate, means for taking the steel from a determined position of the stack-plate and placing the same, a heating plate for receiving the steel transferred from said stack-plate, and means for heating the steel. 80
- 15 8. In a machine for heating steel, the combination of a rotary stack-plate for holding a supply of steel, means for imparting intermittent motion to said stack-plate, means for heating the steel, a carrying-arm for transferring the steel to the heating means, and means for imparting vertically reciprocating and partially rotating movements to said carrying-arm, the movements thereof and those of the stack-plate being timed with respect to each other. 90
- 20 9. In a machine for heating steel, the combination of a rotary stack-plate for holding a supply of steel, means for imparting intermittent motion to said stack-plate, separable heating plates, means for imparting intermittent opening, closing, and inverting motions to said heating-plates, a carrying-arm for transferring the steel to said heating-plates, and means for imparting intermittent vertically reciprocating and partially rotating movements to said carrying-arm, the motions of the stack-plates, heating-plates and carrying-arm being timed with respect to each other. 95
- 25 10. In a machine for heating steel, the combination of means for transferring the steel from a source of supply and placing the same in position for heating, a pair of heating-plates adapted to completely inclose the steel when placed and hold the same during heating, and operating mechanism. 100
- 30 11. In a machine for heating steel, the combination of a carrying-arm for transferring the steel from a source of supply and for placing the same in position for heating, means for imparting intermittent vertically reciprocating and partially rotating movements to said carrying-arm, a pair of heating plates adapted to inclose the steel when placed and hold the same during heating, and means for operating said heating plates. 110
- 35 12. In a machine for heating steel, the combination of a carrying-arm having a suctional terminal for taking steel from a source of supply, means for causing suction, means for imparting motion to said carrying-arm whereby the steel is brought to position for heating, means for releasing the steel from the suction, and means for heating the steel. 115
- 40 13. In a machine for heating steel, the combination of means for warming the steel, means for further heating the steel, a carrying-arm for taking the steel from a source of supply, holding the same while being warmed, and delivering it to the means for final heating, and connections whereby said carrying-arm may be intermittently operated to and from the source of supply and the warming and heating means. 120
- 45 14. In a machine for heating steel, the combination of a carrying-arm for transferring the steel from a source of supply and placing the same in position for heating, means for heating the steel, means for imparting a to and fro motion to said carrying-arm, and means located at the opposite limits of movement of said carrying arm for guiding the latter when reaching the source of supply and when reaching the means for heating. 125
- 50 15. In a machine for heating steel, the combination of a carrying-arm, means for imparting to and fro motion thereto, a stack-plate for holding a supply of steel to be heated, a heating plate for receiving the steel, means for guiding the carrying-arm to a supply of steel on said stack-plate, and means for guiding said arm to the plate for receiving and heating it. 130
- 55 16. In a machine for heating steel, the combination of a carrying-arm having a suctional terminal with a slightly curved or inclined face, a stack-plate for holding pieces of thin steel to be heated, means for imparting motion to said carrying-arm, means for heating the steel, and means for causing suction and for relieving it. 135
- 60 17. In a machine for heating steel, the combination of a carrying-arm adapted to lift and place pieces of steel in position for heating, means for operating said carrying-arm, means for heating the steel, the carrying-arm being provided with a guard-lip for protecting the steel from the direct action of the flame when first placed in position for heating. 140
- 65 18. In a machine for heating steel, the combination of separable heating-plates one of which is adapted to receive and the other to toss the steel, means for operating said plates and means for heating the steel. 145
- 70 19. In a machine for heating steel, the combination of separable heating-plates having their contact surfaces adapted for the admission of air when the steel is heated 150

- and the plates separated, said surfaces being shaped to conform closely to the contour of said steel and to inclose the same, means for heating the steel and means for 5 opening and closing said plates.
20. In a machine for heating steel, the combination of a plate for warming the steel, a pair of separable heating-plates one of which is adapted to receive and the other 10 to toss the steel, means for operating the heating-plates, means for handling, warming, and placing the steel, and means for heating the steel.
21. In a machine for heating steel, the combination of a plate for warming the steel, a pair of separable heating plates having 15 their contact surfaces adapted for the admission of air after the steel is heated, means for handling, warming, and placing 20 the steel, and means for heating the steel.
22. In a machine for heating steel, the combination of separable heating-plates one of which is adapted to receive and the other to toss the steel, a shaft, arms and levers 25 for guiding said plates in a swinging motion over said shaft, and connections for operating said plates in reverse directions in opening and closing them, and means for heating the steel.
23. In a machine for heating steel, the combination of separable heating-plates reformed to provide conjointly a closed recess adapted to surround and protect the steel during heating, means for opening and 30 closing said plates, automatic means for placing the steel between said plates while open and means for heating the steel.
24. In a machine for heating perforate steel, the combination of separable heating- 35 plates having means for locating the steel by the perforations therein, means for opening and closing said plates, means for placing the steel between said plates while open, and means for heating the plates and the in- 40 closed steel.
25. In a machine for heating perforate steel, the combination of a stack-plate having pins for passing through the perforations in the steel stacked thereon, a heating- 45 plate having means for locating the steel by the perforations therein, means for transferring the steel from the stack-plate to the heating-plate, and means for heating the steel.
26. In a machine for hardening steel by 50 heating and chilling, the combination of separable heating-plates for holding the steel, means for operating said plates, means for feeding the steel to said heating-plates, 55 means for heating the steel, means for chilling the hot steel, and means for tossing the hot steel from said heating-plates to the means for chilling.
27. In a machine for hardening steel by 60 heating and chilling, the combination of 65 heating-plates for holding the steel, means for heating and chilling, the combination of 70 means for heating the steel, cold-clamps for chilling the hot steel, means for holding the steel while being heated, and means for automatically transferring the hot steel to said cold-clamps.
28. In a machine for hardening steel by 75 heating and chilling, the combination of separable heating-plates for holding the steel, means for heating the steel, cold-clamps for chilling the steel, and means for inverting said heating-plates, thereby transferring the hot steel to said cold-clamps.
29. In a machine for hardening steel by 80 heating and chilling, the combination of means for heating the steel, a pair of cold- 85 clamps for chilling the steel, operating- means for causing said cold-clamps to exert pressure on the steel while therein, means for automatically transferring the hot steel to said cold-clamps, and means for releasing 90 the chilled steel from said clamps.
30. In a machine for hardening steel by 95 heating and chilling, the combination of means for handling and placing the steel, means for heating the steel, a pair of cold- 100 clamps for chilling the steel, operating- means for causing said cold-clamps to exert pressure on the steel while therein, means for transferring automatically the hot steel to said cold-clamps, and means for releasing 105 the chilled steel from said clamps.
31. In a machine for hardening steel by 110 heating and chilling, the combination of separable heating-plates for holding the steel said plates being perforated for the admission of air after the steel is heated, cold-clamps for chilling the hot steel, and means for tossing the hot steel from said heating-plates to said cold-clamps.
32. In a machine for hardening steel by 115 heating and chilling, the combination of separable heating-plates for holding the steel, said plates being shaped to inclose and conform closely to the contour of said steel and being perforated for the admission of 120 air after the steel is heated, means for handling and placing the steel, means for heating the steel, and means for chilling the steel.
33. In a machine for hardening steel by 125 heating and chilling, the combination of separable heating-plates for holding the steel, said plates being shaped to inclose and conform closely to the contour of said steel and having the continuity of their contact surfaces interrupted for the admission of air after the steel is heated, means for handling and placing the steel, means for heating the steel, and means for chilling the steel.
34. In a machine for hardening steel by 130 heating and chilling, the combination of means for holding the steel, means for heating the steel, clamps for receiving and chilling the hot steel, means for cooling said

clamps, and means for automatically transferring the hot steel to said clamps.

35. In a machine for hardening steel by heating and chilling, the combination of 5 means for handling and placing the steel, means for heating the steel, cold-clamps for chilling the steel, one of said clamps being stationary and the other movable, means for operating the movable clamp, and means for 10 automatically transferring the hot steel to said movable clamp.

36. In a machine for hardening steel by heating and chilling, the combination of a 15 stack-plate adapted to receive a pile of superimposed pieces of steel, a heating plate for receiving the steel, a lifting and carrying-arm for transferring the steel from the stack-plate to the heating-plate, means for chilling the steel, and means for causing 20 transit of the steel from the heating-plate to the chilling means.

37. In a machine for hardening steel by heating and chilling, the combination of a 25 stack-plate for the supply of steel, means for supporting the steel while heating, means for transferring the steel to said supporting means, means for warming the steel prior to its placement on said supporting means, means for heating the steel, cold-clamps for 30 chilling the hot steel, and means for transferring the hot steel to said cold-clamps.

38. In a machine for hardening steel by heating and chilling, the combination of a 35 stack-plate for holding the supply of steel to be heated, separable heating-plates for holding the steel during heating, means for heating the steel, cold-clamps for chilling the steel, means for transferring the steel from the stack-plate to the heating-plates 40 and means for tossing the hot steel from the heating-plates to the cold-clamps.

39. In a machine for hardening steel by heating and chilling, the combination of a 45 rotary stack-plate for holding stacks of steel, means for imparting intermittent rotary motion to said stack-plate, means for heating the steel, means for transferring the steel from said stack-plate to the heating means, cold-clamps for chilling the hot steel, 50 means for transferring the hot steel to said cold-clamps, and means for causing said clamps to exert pressure on the hot steel therein.

40. In a machine for hardening perforate 55 steel by heating and chilling, the combination of a rotary stack-plate having pins for holding the steel, separable heating-plates having means for locating the steel by the perforations therein, means for taking the steel from said stack plate and transferring the same to said heating-plates, means for chilling the steel, and means for transferring the hot steel from said heating-plates to the chilling means.

65. 41. In a machine for hardening steel by

heating and chilling, the combination of means for heating the steel, cold-clamps for chilling the hot steel, one of said clamps being stationary and the other movable, means for transferring the hot steel to said movable clamp, a lever-arm having a roller adapted to exert pressure on said movable clamp and means for operating said lever-arm suddenly, and for bringing the same to a position whereby the hot steel is compressed between the two clamps while at the same time rebounding is prevented. 75

42. In a machine for acting on metal, the combination of means for acting and producing a desired effect on the metal, a carrying-arm for transferring the metal from a supply to the means for acting thereon, a rod to which said carrying-arm is secured, means for guiding said rod vertically, a hub to which the lower part of said rod is rigidly secured, and connections with said hub whereby said rod is supported and moved vertically and said carrying-arm turned to and from the supply to the means for acting on the metal. 85

43. In a machine for acting on metal, the combination of a carrying-arm for supplying the metal to be acted upon, an operating rod to which the upper end of said carrying-arm is rigidly secured, means for guiding 95 said rod, a hub having oppositely projecting arms, trunnions journaled in said arms, sleeves connected with said trunnions, pull-rods passing through said sleeves, clamps on said rods for limiting their pulling movement respectively, levers to which one end of said pull-rods are attached, and cams adapted to raise and lower said levers independently of each other whereby back and forth and turning movements may be imparted to said rod and said carrying-arm. 100

44. In a machine for hardening metal by heating and chilling, the combination of a pair of separable plates adapted to receive the metal between them, means for opening and closing said plates, means for placing the metal between said plates while open, means for heating the plates and the enclosed metal, means for chilling the metal, means for shifting said plates in closed relation from the heating means to the chilling means, and means for opening said plates and for automatically transferring the metal therefrom to said chilling means. 115

45. In a machine for hardening metal, the combination of a pair of opposed cold-clamps having continuous metallic surfaces conforming to the contour of the article to be hardened and adapted to receive the latter between them, and means for closing 120 said clamps with a forcible blow upon the heated metal.

46. In a machine for hardening metal, the combination of a pair of opposed cold-clamps having continuous metallic surfaces 125

conforming to the contour of the article to be hardened and adapted to receive the latter between them, means for closing said clamps with a forcible blow upon the heated 5 article, and means for automatically locking said clamps against rebounding.

47. In a machine for hardening metal, the combination of a pair of opposed cold-clamps having continuous metallic surfaces 10 conforming to the contour of the article to be hardened and adapted to receive the latter between them, means for heating said article to be hardened, means for automatically transferring the heated article 15 to the cold-clamps, and means for closing said clamps with a forcible blow.

48. In a machine for hardening metal by heating and chilling, the combination of a pair of plates adapted to receive the metal 20 between them, said plates being shiftable about a common axis, means constantly tending to move said plates toward each other, and means for positively shifting said plates about their common axis in opposition to the means which tend to move them toward each other.

49. In a hardening machine, a chilling device comprising a pair of opposed cold-clamps having continuous chilling surfaces 30 conforming to the contour of the article to be hardened and adapted to receive the latter between them, means for operating said clamps, and means for removing scale from said clamps.

35 50. In a hardening machine, a chilling device comprising a pair of opposed cold-

clamps having continuous chilling surfaces conforming to the contour of the article to be hardened and adapted to receive the latter between them, means for opening and closing 40 said clamps, and means for directing an air blast across the surface of the lower clamp while said clamps are open.

51. In an apparatus for tempering blades, means to heat the blades one by one while 45 protecting them from contact with the heating medium, means to subject the hot blades to simultaneous cooling and rapid compression, a device to deliver the hot blades one by one to said cooling and compressing 50 means, and an instrumentality to remove automatically the cooled blade from said means.

52. In apparatus for tempering blades, a heater to receive and protect a blade from 55 direct contact with the heating medium, means to retain the blade in the heater and release it at a predetermined time, means to simultaneously cool and subject the hot blade to pressure, and means for transferring the latter from the heater to the cooling and pressure-producing means.

53. In apparatus for tempering blades, means to receive temporarily and protectively inclose a blade while said means is maintained at a high temperature, and a device to effect the release of the blade from 60 said means.
